UNITED STATES PATENT OFFICE.

ALFRED E. JERNANDER, OF FARIBAULT, MINNESOTA.

LAWN-MOWER SHARPENER.

1,031,006.

Specification of Letters Patent.

Patented July 2, 1912.

Application filed July 27, 1911. Serial No. 640,814.

To all whom it may concern:

Be it known that I, ALFRED E. JERNANDER, a citizen of the United States, residing at Faribault, in the county of Rice and State 5 of Minnesota, have invented a new and useful Lawn-Mower Sharpener, of which the following is a specification.

My invention relates to devices for sharpening lawn-mowers; and the main object 10 is to provide a durable and efficient sharpening device which may be attached to a lawn-mower in such position relative to the cutters that the latter may be sharpened by the ordinary operation of the lawn-mower. 15 This and other objects I attain by the novel construction and combination of parts illustrated in the accompanying drawing, in which—

Figure 1 is a top or plan view of a lawn- 20 mower equipped with my sharpening device. Fig. 2 is a section on the line *a—a* Fig. 1 with the handle of the mower omitted. Fig. 3 is a portion of the upper left hand corner of Fig. 2 modified. Fig. 4 is a de- 25 tail bottom view of the clamping plate 11 in the other views.

Referring to the drawing by reference numerals, 1 designates the handle, 2 the cheek plates and 3 the front bar which se- 30 cures said plates together and with the fixed cutter bar 4 form the frame of the machine. Said frame is supported by the usual rear roller 5 and two ground wheels 6; the lat- 35 ter serving also as driving wheels to rotate the winged cutter shaft 7, on which spirally curved cutters 8 are secured and adapted to co-act with the fixed cutter 4, all of which, together with the ratchet mechanism (not shown) connecting the ground wheels with 40 the cutter, may be of any of the well known forms and thus need not here be further described.

On the front frame bar 3 I clamp by clips 9 and nuts 10 thereon two bracket plates 11, 45 each of which has a bracket portion 12, in which is secured by a set-screw 13 the upper end of an angularly bent spring 14, which may be plain as in Fig. 3 or may have a coil 15 as shown in Figs. 1 and 2, to increase 50 the flexibility of the spring.

The downward arm of each spring is formed with a horizontal end portion 16, on which is adjustably secured by a set-screw 17 a casting 18. Said casting is formed 55 with a plate 19, which by wood-screws 20, or other means, is secured to the front side

of a channel-shaped wooden bar 21, in the channel or groove of which is placed a metallic strip 22 (see Fig. 2) on which act the ends of adjustment screws 23 to take up 60 the wear of a stone 24, which is held in the groove of bar 21 by frictional contact with the sides of the groove, the sides being sprung toward the stone by clamps 25 which are preferably made integral with the cast- 65 ings 18—19, and are each provided with a screw 26 by which to press upon the adja- cent side of the channel bar. In Fig. 2 the head of the feed screw 23 is broken away to expose the arm 16 of the spring, but still 70 23 in Figs. 1 and 2 will make that part of the structure plain.

In Fig. 4 it is best shown that the plate 11 is preferably provided with notches 27 for the clips 9, so that the clips may be 75 widened or closed according as the bar 3 may be extra large or small in diameter. In all cases where the bar 3 is round the edges of the groove 28 of the plate will take a firm hold of the bar, the groove being made on a 80 smaller radius than any of the bars.

In Fig. 3 is shown that when the bar 3* is rectangular in cross section its upper side will fit the underside of the plate 11 without entering into the groove 28 of same. 85 The stone slab or strip 24 may be of any suitable kind of stone, but I prefer stones made of emery, corundum and carborundum, especially the latter, as the same may be used dry at high speed without taking 90 the temper out of the cutters.

In the operation the device is secured on the machine as shown and adjusted with the straight rear edge of the stone in contact with the edges of the cutters 8, and the ma- 95 chine is pushed along on the floor or on the ground so that the cutter shaft 7 rotates, the cutters will then in passing the stone become sharpened; the spring 14 holding the stone in suitable contact with the passing 100 cutters. By means of the screws 17 the stone may be regulated up or down according to the size of the lawn-mower and by the screws 13 the sharpening attachments may be adjusted backward and forward in the machine ac- 105 cording to the size, and arrangements of the parts of the mower. The device may be used with or without water or moisture on the stone. If the lawn-mower is much in use, especially on ground where it is exposed 110 to gravel, sand or other matter to dull it, the sharpening device may remain perma-

nently on it, otherwise it may be removed until such times as it will occasionally be needed.

What I claim is:—

- 5 1. In a lawn mower sharpener, a pair of brackets securable upon a bar of the mower frame, a spring arm extending horizontally and then downwardly from each bracket, a secondary bracket secured on the downward portion of each spring arm and formed with a U-shaped clamp or fork, an integral wooden bar held near its ends in said forks and having in one side an angular groove, an abrading member inserted in said groove, 10 and a set-screw through one tine of each fork, to press with its end upon the side of the grooved bar, so as to spring the same into squeezing engagement with the abrading member and thereby hold the latter firmly in the groove.
- 15 2. In a lawn mower sharpener, a pair of brackets securable upon a bar of the mower frame, a spring arm extending horizontally and then downwardly from each bracket, a secondary bracket secured on the downward portion of each spring arm and formed with a fork, an integral wooden bar held near its ends in said forks and having in one side an angular longitudinal groove, an abrading member inserted in said groove, and a set-screw through one tine of each fork, for closing the wooden bar against the sides of the abrading member, to hold the latter
- 20 firmly in the groove; a metal strip extending along the bottom of the groove so as to support the abrading member, and feed screws arranged to press said strip against the abrading member and thereby easily adjust the latter to the best working position.
- 25 3. In a lawn mower sharpener, a pair of brackets having clamping means for securing same on a bar of the mower frame and provided with a hole in each bracket, a spring arm having a substantially horizontal and also a vertical portion, a forked bracket having a hole receiving each of the vertical portions, set-screws holding the spring arms adjustably in the forked brackets and in the holes of the first-mentioned brackets, a longitudinally grooved wooden bar secured in the forks of the forked brackets, feed screws through the bottom of the groove in the wooden bar, a metal strip in the groove, and an abrading element at the outer side of said strip in the groove, and set-screws in one tine of each fork arranged to press on the wooden bar and close it tightly against the sides of the abrading element.
- 30 In testimony whereof I affix my signature, in presence of two witnesses.

ALFRED E. JERNANDER.
